UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

METHOD OF AND APPARATUS FOR CASTING SLUGS.

1,259,671.

Specification of Letters Patent. Patented Mar. 19, 1918.

Application filed December 12, 1916. Serial No. 136,407.

To all whom it may concern:

Be it known that I, JOHN R. ROGERS, a citizen of the United States, residing at Brooklyn, in the county of Kings and State 5 of New York, have invented certain new and useful Improvements in Methods of and Apparatus for Casting Slugs, of which the following is a specification, reference being had therein to the accompanying drawing.

10 In my copending application, Serial No. 136,406, I have disclosed a new method for preparing tabular printing forms, involving the production of the printing slugs with rule-holding notches, which are offset or located 15 in different relative longitudinal positions on two or more of the slugs. The present invention, specifically, is intended to adapt the linotype and kindred machines to produce such slugs without requiring any 20 attention on the part of the operator and without involving any material change in the existing parts, as will be fully set forth in the detailed description to follow.

In the accompanying drawings, I have 25 shown my invention in preferred form and by way of example and as applied to a machine of the class stated, but obviously many changes and variations may be made therein and in its mode of application which will 30 still be comprised within its spirit. Generally speaking, I desire it to be understood that I do not limit myself to any specific form or embodiment, except in so far as such limitations are specified in the claims.

35 Referring to the drawings:

Figure 1 is a front view of a portion of a linotype machine having my invention applied thereto;

Fig. 2 is a section on the line 2—2 of 40 Fig. 1;

Figs. 3 and 4 are detail-views;

Fig. 5 is an enlarged section taken horizontally through the casting devices; and

Fig. 6 is a similar view showing the parts 45 in different relative positions.

The matrices which are stored in a channeled magazine (not shown) are released therefrom in the required order and delivered to the assembler A, wherein they are 50 composed in line in the usual way. When the composition of the line is completed, the assembler is raised and brought into registration with the intermediate channel B, and the line transferred therethrough to the 55 first elevator C, which then carries the line

downwardly and locates it between the clamping jaws E, E', and in front of the casting mold D. The jaws are supported in the relatively fixed vise frame O, while the mold is carried by the wheel or disk D¹, 60 adapted to be shifted facewise to advance the mold up against the matrix line and hold it in firm contact therewith during the casting operation. The parts so far described are all of standard construction and are 65 operated in the customary manner, and in the drawings they are shown in their casting relation with the matrix line properly locked up and justified.

As herein illustrated, the composed line 70 comprises the regular character matrices X, the blank or rule notch producing matrices X¹ and the expandible spacer Y. The blank matrices X¹ are assembled in the succeeding lines in the same relative position, and, consequently, unless means were otherwise provided, such matrices would be presented to the mold in the same position with respect thereto.

As before stated, it is one of the objects 80 of my present invention to cast the slugs so that the rule notches will be offset or located in different longitudinal positions on two or more thereof. To attain this result, I propose to vary the position of the successive matrix lines longitudinally with reference to the mold, and in the present instance this is accomplished by the adjustment of the clamping jaws between which the lines are justified preparatory to casting. Ordinarily, the righthand jaw E is 85 normally fixed, while the lefthand jaw E' is movable to a slight extent under the influence of the justifying devices to compress the composed line endwise up against the 90 fixed jaw. In carrying out my invention, I mount the jaw E so that it may be set in slightly different positions, in such manner that the successive matrix lines, when compressed between it and the companion jaw, 95 will be caused to stand in correspondingly different positions longitudinally of the mold. Consequently, when the successive lines are composed with the blank matrices 100 in the same relative location therein, such 105 matrices will be presented to the mold at different points in the length thereof so as to produce the rule-notches in the resultant slugs in correspondingly different positions, as required. This is clearly represented in 110

Figs. 5 and 6, which show the casting devices in the different relative positions described, the molds also being shown with slugs Z cast therein. It will be noted that in Fig. 5 the jaw E occupies a position nearer to the right end of the mold slot than it does in Fig. 6, and that consequently the positions of the blank matrices X¹ vary to a like extent. The result is that the blank 10 matrices produce in the slugs Z rule-notches Z¹ which are offset or located in different positions in the length thereof, as shown. In the drawings, the amount of displacement of the parts is somewhat exaggerated 15 for the sake of clearness. In practice, however, the adjustment of the jaws is extremely slight, and only of an extent sufficient to vary the relative positions of the rule-notches in the successive slugs a few thousandths of 20 an inch.

Any suitable mechanism may be employed for effecting the adjustment of the jaw E¹, either manual or automatic. In the present instance, I have provided automatic mechanism which acts to effect the adjustment of the jaw at succeeding casting operations or when successive matrix lines are composed and forwarded for casting. In the embodiment illustrated, such mechanism comprises 30 a circular gage plate or disk F fixed to a shaft F¹ rotatably mounted in a bearing sleeve F² screwed into a part of the jaw E and capable of a slight axial movement therein. The disk F has a plain front face 35 which lies flatly up against the rear end of the jaw E or its supporting slide, while its rear face presents a plurality of depressions F³ and intermediate projections F⁴ adapted to coöperate with a fixed stop F⁵ secured to 40 the vise frame. As a result of this construction, when the disk F is rotated to bring one of its depressions opposite the fixed stop F⁵, the jaw E is permitted, during the justification of the line, to assume its rightmost position, as indicated in Fig. 5; and when the 45 disk is rotated to bring one of its projections F⁴ opposite the fixed stop, the jaw is shifted to the left and is held, during the justification of the line, in its leftmost position, as 50 shown in Fig. 6. Of course, the change in position of the jaw E is determined in extent by the difference in thickness of the recessed and unrecessed portions of the gage plate or disk F.

55 The rotation of the disk F is effected periodically by the raising of the assembler elevator A. As shown in Fig. 1, the shaft F¹ is provided at its outer end with a ratchet wheel F⁶ which is arranged in position to be 60 engaged by a pawl F⁷ carried by the assembler, the pawl being located in such position thereon as to engage and actuate the ratchet wheel just prior to the transfer of the line therefrom. At each operation of the assembler, therefore, the disk F is rotated the dis-

tance of one ratchet tooth so as to bring either a recess F³ or a projection F⁴ opposite the fixed stop F⁵ to effect the adjustment of the jaw E, and consequently the composed line, when locked up between the clamping jaws, is caused to assume a position toward the left or right of the casting mold, as the case may be. The position of the jaw being thus changed automatically after the composition of each line, the successive matrix lines with their blank matrices will be presented to the mold in different longitudinal positions, whereby the slugs will be cast in two sets and with rule receiving notches or recesses offset or located in different longitudinal positions in the respective sets. 70 75 80

In order to cast the slugs in the usual manner and without changing the position of the succeeding matrix lines with reference to the mold, provision is made for rendering 85 the jaw adjusting mechanism inactive. In the present arrangement, this result is attained by pivoting the pawl F⁷ upon the assembler A so that it may be swung forwardly out of engaging relation to the ratchet wheel F⁶, as indicated by the dotted lines in the lower part of Fig. 3.

As previously stated, I have shown my invention merely in preferred form and by way of example, and it will be obvious that 95 many changes and variations may be made therein without departure from its scope. Thus, the jaw adjusting mechanism may be modified in construction, and, if desired, operated from some other part of the machine, or even by hand. These and other changes will readily suggest themselves to those skilled in the art.

It will also be understood that my improved mechanism may be made use of for 105 some other purpose than that herein mentioned, it being useful in any connection where it is desired to change the position of the matrix lines with reference to the mold in the manner shown and described. 110

Having thus described my invention, its construction and mode of operation, what I claim and desire to secure by Letters Patent of the United States, is as follows:

1. In a typographical casting machine, 115 the combination of a mold, means for supporting a matrix line in operative relation thereto, and periodically actuated mechanism whereby the mold and matrix line are caused to occupy one or another of different relative positions longitudinally of the mold, as required. 120

2. In a typographical casting machine, the combination of a mold, means for supporting a matrix line in operative relation 125 thereto, and periodically actuated mechanism whereby the matrix line is located in one position or another longitudinally of the mold, as required.

3. In a typographical casting machine,

the combination of a mold, means for supporting matrix lines in operative relation thereto, a pair of clamping jaws which receive the lines therebetween, one of said 5 jaws being normally fixed and the other movable to compress the lines, and periodically actuated mechanism for setting the normally fixed jaw in different operative positions to vary the location of the matrix 10 lines longitudinally of the mold.

4. In a typographical casting machine, the combination of a mold, means for supporting matrix lines in operative relation thereto, a pair of clamping jaws which receive the lines therebetween, one of said 15 jaws being normally fixed and the other movable to compress the lines, and periodically actuated mechanism for setting the normally fixed jaw in different operative 20 positions, the said mechanism being controlled by a moving part of the machine.

5. In a typographical composing and casting machine, the combination of means for composing the matrices in lines, a mold, 25 means for presenting and supporting the composed matrix lines in operative relation to the mold, a pair of clamping jaws which receive the lines therebetween, one of the jaws being normally fixed and the other 30 movable to compress the lines, and periodically actuated mechanism controlled by the composing means for setting the normally fixed jaw in different operative positions.

6. In a typographical composing and 35 casting machine, the combination of a movable assembler wherein the matrices are composed in lines, a mold, means for presenting and supporting the composed matrix lines in operative relation to the mold, a pair of 40 clamping jaws which receive the lines therebetween, one of the jaws being normally fixed and the other movable to compress the lines, and mechanism actuated periodically by the movement of the assembler for setting 45 the normally fixed jaw in different operative positions.

7. In a typographical casting machine, the combination of a mold, means for supporting a matrix line in operative relation thereto, and periodically actuated mechanism 50 whereby the mold and matrix line may be caused to occupy one or another of different relative positions longitudinally of the mold, said mechanism being controlled from a 55 moving part of the machine.

8. In a typographical composing and casting machine, the combination of means for composing the matrices in line, a mold, 60 means for presenting and supporting the matrix line in operative relation to the mold, and periodically actuated mechanism controlled by the composing means whereby the mold and matrix line may be caused to occupy one or another of different relative 65 positions longitudinally of the mold, as required.

9. In a typographical composing and casting machine, the combination of means for composing the matrices in lines, a mold, means for presenting and supporting the matrix lines in operative relation to the 70 mold, and automatic mechanism acting as the successive matrix lines are composed to set said lines and the mold in different relative positions longitudinally of the mold.

10. In a typographical composing and 75 casting machine, the combination of means for composing the matrices in lines, a mold, means for presenting and supporting the composed matrix lines in operative relation to the mold, and automatic mechanism acting as the successive matrix lines are composed to locate them in different positions 80 longitudinally of the mold.

11. In a typographical composing and casting machine, the combination of means 85 for composing the matrices in lines, a mold, means for presenting and supporting the matrix lines in operative relation to the mold, a pair of clamping jaws which receive the lines therebetween, one of the jaws being 90 normally fixed and the other movable to compress the lines, and automatic mechanism acting as the successive matrix lines are composed to set the normally fixed jaw in different operative positions. 95

12. In a typographical casting machine, the combination of a mold, a matrix line containing a blank or rule-notch producing matrix, and periodically actuated mechanism whereby the mold and matrix line are 100 caused to occupy one or another of different relative positions longitudinally of the mold, as required.

13. In a typographical composing and casting machine, the combination of means 105 for composing matrix lines of the same length and with blank or rule-notch producing matrices in the same relative location therein, a mold, means for presenting and supporting the matrix lines in operative relation to the mold, and automatic mechanism acting as the successive matrix lines are composed to locate them in different relative 110 positions longitudinally of the mold.

14. In a typographical casting machine, 115 the combination of a mold, means for supporting matrix lines in operative relation thereto, a pair of clamping jaws which receive the lines therebetween, one of said jaws being normally fixed and the other 120 movable to compress the lines, and mechanism for setting the normally fixed jaw in different operative positions, said mechanism including a movable gage plate having portions of different thicknesses and arranged between the jaw and a relatively 125 fixed part of the machine.

15. In a typographical composing and casting machine, the combination of a movable assembler wherein the matrices are com- 130

- posed in line, a mold, means for presenting and supporting the composed matrix lines in operative relation to the mold, a pair of clamping jaws which receive the lines therebetween, one of the jaws being normally fixed and the other movable to compress the lines, and automatic mechanism for setting the normally fixed jaw in different operative positions, the said mechanism including the rotary gage plate or disk F, its supporting shaft F¹ provided with the ratchet wheel F⁶, and the pawl F⁷ mounted on the movable assembler and adapted to engage and actuate the ratchet wheel.
16. In a typographical casting machine, the combination of a mold, means for supporting matrix lines in operative relation thereto, a pair of clamping jaws which receive the lines therebetween, one of said jaws being normally fixed and the other movable to compress the lines, periodically actuated

mechanism for setting the normally fixed jaw in different operative positions, and means whereby said mechanism may be rendered inactive at will. 25

17. In the method of casting slugs with offset or differently located rule-holding notches, making up matrix lines with blank or rule-notch-producing matrices located in the same relative position therein, and presenting the matrix lines to a casting mold in different relative positions longitudinally thereof. 30

18. In the method of casting printing slugs, making up matrix lines of the same length, and presenting the successive matrix lines to a casting mold alternately in first one and then the other of two different relative positions longitudinally thereof. 35

In testimony whereof I have affixed my 40 signature.

JOHN R. ROGERS.
